UNITED STATES PATENT OFFICE.

WILLIAM H. LLOYD, OF BOSTON, MASSACHUSETTS, ASSIGNOR TO THE J. L. MOTT IRON WORKS, OF NEW YORK, N. Y.

DESIGN FOR A BASIN-SLAB.

SPECIFICATION forming part of Design No. 32,047, dated December 26, 1899.

Application filed December 4, 1899. Serial No. 739,204. Term of patent 14 years.

To all whom it may concern:

Be it known that I, WILLIAM H. LLOYD, a citizen of the United States, residing at Boston, in the county of Suffolk and State of Massachusetts, have invented and produced a new and original Design for Basin-Slabs, of which the following is a specification, reference being had to the accompanying drawings, in which—

10 Figure 1 is a plan view of the basin-slab, showing my new design; and Fig. 2 is a vertical longitudinal section of the same.

As shown in the drawings, the leading or material feature of my design consists in the 15 elliptical periphery or outline of the basin and the elliptical outline of the bowl-opening in the basin, the latter being eccentric to the former.

The design of the basin comprises the elliptical periphery or outline *a* and the elliptical outline *b* of the bowl-opening, the said ellip-

tical outline of the bowl-opening being eccentric to the elliptical periphery of the basin-slab. The edge of the elliptical outline *a* is molded at *c*, and the surface *d* adjacent to the 25 said elliptical outline *a* is curved and raised above the flat portion *e* of the surface of the slab. The edge *b* of the elliptical bowl-opening is rounded. Raised circular portions *f*, *f'*, and *f''* are provided adjacent to one another 30 at one side of the slab, and in these raised portions openings 2 and 3 are provided.

What I claim is—

The design for a basin-slab, substantially as shown and described.

Signed by me this 24th day of November, 1899.

WILLIAM H. LLOYD.
